COMBINED BOTTLE OPENER AND FLEXIBLE TUBE ROLLING KEY

Harold Brown, 2236 S. Milwaukee St., Denver, Colo.,
assignor of one-third each to Morris Kaplan and Harold
S. Tuft, both of Denver, Colo.

Filed Oct. 3, 1963, Ser. No. 76,857

Term of patent 7 years

(Cl. D44—29)

FIG. 1 is a top edge view of a combined bottle opener and flexible tube rolling key showing my new design;

FIG. 2 is a front face view; and

FIG. 3 is a side edge view thereof.

I claim:

The ornamental design for a combined bottle opener and flexible tube rolling key, as shown.
